DEVICE FOR PACKAGING FLAT FLEXIBLE ARTICLES

Robert B. Brown, Greenville, S. C.

Application October 24, 1951, Serial No. 252,939

5 Claims. (Cl. 226—18)

1

This invention relates to apparatus for packaging substantially flat flexible objects and more especially to a device and method for inserting relatively flat flexible articles, such as sheets of cardboard or the like on which strips or slices of bacon are positioned, into paper or cellophane bags.

It is well known to those familiar with the art that in the process of preparing bacon and analogous articles for display, the bacon is sliced in relatively thin narrow strips and a plurality of these slices of bacon are usually positioned on a relatively heavy sheet of paper or cardboard with the slices of bacon arranged in partially overlapping relation to each other and the cardboard having the bacon thereon may sometimes herein after be referred to as a sheet of bacon.

Now, after the sheet of bacon has been arranged in the manner described, according to the present invention, it is inserted in a transparent bag or container, preferably made from cellophane or the like, which is substantially of the same shape and size as the sheet of bacon. Heretofore, bacon has been wrapped, either automatically or by hand and if it was desired to put the same in a bag, it was necessary to insert the sheet of bacon in the bag by hand and, due to the size of the bag being substantially the same size as the sheet of bacon, this has been a rather tedious and painstaking task, since it has been necessary for the operator to hold the bag open with one hand while bending the sheet of bacon in the center thereof to permit it to be inserted in the bag and then straightening the sheet of bacon by hand. It is evident that inserting these sheets of bacon in bags by hand has been a costly procedure resulting in a relatively high cost to the grocer, and, of course, to the consumer; consequently, a wrapper is usually used and this is not as satisfactory as a bag and is more expensive and usually requires expensive wrapping machinery.

It is, therefore, an object of this invention to provide a method of packing sheets of bacon or the like, which method is carried out by the use of a packaging device substantially in the form of an open-topped channel-shaped or U-shaped chute which has upwardly diverging and forwardly converging walls at the rear end thereof provided with flanges on the upper edges thereof and whereby a sheet of bacon may be slid along the chute between the forwardly converging walls and beneath the flanges to thereby cause the sheet of bacon to be bowed and resulting in the distance between opposite side edges

of the sheet of bacon being gradually decreased as a sheet of bacon is moved along said chute by an operator. The chute has means on the front end thereof for holding a bag. The bag holding means is so arranged as to cause the bag to be opened as it is slid over the same by the operator to thus present the open end of the bag to the portion of the chute within which the sheet of bacon is bowed and to thereby facilitate sliding the sheet of bacon into the bag as it is slid along said chute. It is evident that this operation can be performed very quickly and, therefore, the operator can slide these sheets of bacon into the bags about as fast as he can pick up the sheets of bacon and the bags and position the bags over the corresponding front end of the chute.

It is another object of this invention to provide a simple means for packaging sheets of bacon in bags which is light in weight, durable and may be easily constructed with a minimum of parts.

Some of the objects of the invention having been stated, other objects will appear as the description proceeds when taken in connection with the accompanying drawings, in which—

25 Figure 1 is an isometric view of the improved packaging device showing the manner in which it is used and showing the same mounted upon a table and a conveyor adjacent the table, the conveyor and the table being shown schematically;

30 Figure 2 is a longitudinal vertical sectional view through the packaging device showing a bag positioned thereon and a sheet of bacon positioned in the chute preparatory of being inserted in the bag;

35 Figure 3 is a top plan view of the packaging device;

Figure 4 is a side elevation of the device looking up at the bottom of Figure 3;

40 Figure 5 is a rear end elevation of the packaging device;

Figure 6 is a front end elevation of the packaging device with a portion of the standard therefor broken away.

45 Referring more specifically to the drawings, sheets of bacon broadly designated at S are usually moved along on a conveyor 10 which is positioned immediately adjacent a table 11. As is well known to those familiar with the art, each of the sheets of bacon usually comprises a sheet of flexible or bendable material 12, such as paper, paper board, cardboard or the like, on which a plurality of relatively narrow thin strips or slices of bacon 13 are positioned, there usually being a pound or a half pound of bacon positioned on each of the sheets of cardboard 12.

As the sheets of bacon S move along with the conveyor 10, in the direction of the lower arrow in Figure 1, each of the same is picked up by the operator and inserted in a rectangular bag B which is substantially of the same size and shape as the sheet of bacon S. This bag B is preferably made from a transparent material, such as cellophane and the like, so the contents thereof may be observed when the sheet of bacon S is displayed in the bag B.

The improved packaging device comprises an elongated open-topped substantially channel-shaped or U-shaped chute broadly designated at 20, which includes successively aligned communicating sections, namely, a rear or ingress section 21, an intermediate section 22 and a front or bag holding section 23. The chute 20 is preferably made from a relatively thin rigid material such as sheet metal. The ingress and intermediate sections 21 and 22 are of generally U-shaped or channel-shaped configuration in cross-section, and act as confining members and the front or bag holding section 23 is shaped similar to a shovel or dust pan.

The chute 20 has a flat bottom comprising bottom members 24, 25 and 26 which define the bottoms of the respective sections 21, 22 and 23. The bottom member 24 is preferably trapezoidal in plan. The bottom 25 of the intermediate section 22 is in the shape of an elongated rectangle and the bottom 26 of the front or bag holding section 23 is also preferably trapezoidal in plan. The proximate ends of the bottom members 24 and 26 are of substantially the same dimensions as the opposite ends of the substantially rectangular bottom member 25 of the section 22 and are suitably connected thereto, as by welding, or may be integral therewith, if so desired.

It will be noted that the outer or front end or base edge of the bottom member 26 of the section 23 is substantially wider than the outer or rear end or base edge of the bottom member 24 of the section 21. The outer or front end of the bottom member 26 is also substantially the same width as the distance between the upper edges of the side walls of the intermediate section 22. The rear or ingress section 21 is provided with upwardly and outwardly diverging side walls 27 and 28, the lower edges of which are connected to opposite side edges of the bottom member 24 and may be integral therewith. These angularly disposed side walls 27 and 28 also converge forwardly and the upper edges thereof extend in substantially parallel relation to the bottom member 24.

The opposite side edges of the bottom member 25 of the intermediate section 22 have the lower edges of upwardly and outwardly diverging side walls 31 and 32 connected thereto or integral therewith, the rear edges of which are connected to the front edges of the upwardly diverging walls 27 and 28 of the rear section 21, as by welding, or they may be integral therewith. It will be noted that the walls 31 and 32 extend forwardly in substantially parallel relation to each other. The walls 31 and 32 also terminate flush with the upper edges of the side walls 27 and 28 and extend in substantially parallel relation to the bottom member 25. Suitably secured to and projecting inwardly from the upper edges of the side walls 27, 31 and 28, 32 are respective confining flanges 34 and 35, the inner or proximate edges of which extend in substantially parallel relation to the upper edges of the corresponding side walls 27, 31 and 28, 32. The rear edges of the confining

flanges 34 and 35 are preferably tapered rearwardly and outwardly as at 36 and are rounded at their front ends as at 37.

The rear edges of substantially triangularly-shaped side walls 40 and 41 are connected to the front edges of the side walls 31 and 32 of the intermediate section 22, as by welding. The lower edges of these side walls 40 and 41 are connected to the opposite side edges of the bottom member 26 of the bag holding section 23. Of course, these side walls 40 and 41 may be integral with the bottom member 26 of the section 23, if desired.

It will be observed in Figures 1, 2 and 3 that the front sharp ends of the side walls 40 and 41 terminate substantially flush with the front edge of the bottom member 26 thus providing a rearwardly and upwardly slanting upper edge to the side walls 40 and 41. It is thus seen that the front end of the chute 20 presents a narrow flat edge about which the open end of the bag B may easily be placed and then the bag B may be slid rearwardly to the juncture of the side walls 31 and 40 and 32 and 41 of the adjacent sections 22 and 23 thus causing the bag B to be opened for receiving the sheet of bacon S.

The chute 20 of the packaging device is suitably secured, as by spot welding, to a standard broadly designated at 45 which is shown as being made from a piece of strap material having a horizontal portion 46 extending forwardly from a vertical portion 47. The lower end of the standard 45 is bent at right angles to form a foot portion 48. The horizontal leg of the standard 45 extends substantially the same length as the bottom member 25 of the intermediate section 22 and a suitable gusset plate 51 is welded or otherwise secured to the rear surface of the vertical leg 47 of the standard 45 and supports the rear section 21. The vertical leg 47 of the standard 45 has an angle clip 52 suitably secured thereto, as by spot welding, and the horizontal leg of the angle clip 52 and the horizontal portion 48 of the standard 45 are penetrated by bolts 53 for securing the standard and the chute 20 to the table 11.

It is preferable that the rearmost edges of the side walls 27 and 28 of the section 21 of the chute 20 extend downwardly and rearwardly at an angle from the rear ends of the confining flanges 34 and 35 and that the rear edge of the bottom member 24 is disposed rearwardly of the vertical plane of the rear ends of the confining flanges 34 and 35 to facilitate inserting each of the sheets of bacon S into the ingress end of the chute 20.

It is thus seen that I have provided means for carrying out the method of passing the sheets of bacon between a pair of confining members, such as the junctures of the walls 27, 31 and 28, 32 with the respective confining flanges 34 and 35, and wherein the confining members have a distance therebetween which is less than the width of the sheet of bacon S so the sheet of bacon will be bowed or bent intermediate its ends as it is passed between the confining members and whereby the distance from one side edge to the opposite side edge of each of the sheets of bacon S is substantially less than the distance from one edge to the opposite edge of the bag B.

Thus, each of the sheets of bacon S may be taken off of the conveyor 10, by the operator grasping the end of the corresponding sheet of bacon furthest from the chute 20, and then the operator slides the sheet of bacon forwardly and inwardly between the walls 27 and 28 of the ingress section 21 and immediately beneath the confining flanges 34 and 35. The distance be-

tween the uppermost rear corners of the walls 27 and 28 of the ingress section 21 is preferably substantially greater than the distance from one side edge to the other of the sheet of bacon S so the sheet of bacon may be readily inserted in the ingress end of the chute 20.

Now, as the operator slides the sheet of bacon S forwardly, in the direction of the arrow in the upper portion of Figure 1, the opposite edges of the sheet of bacon S will be caused to move towards each other as the central portion thereof is bowed downwardly whereupon the sheet of bacon may be slid into the bag B previously positioned over the bag holding section 23 in the manner heretofore described. As the sheet of bacon S is slid into the bag B, the bag B may be released by the operator thus permitting the same to move off of the bag holding section 23 of the chute 20 to thus complete the packaging operation.

It is thus seen that the packaging of each of the sheets of bacon S may be performed by a single uninterrupted forward stroke of the operator's hand as he moves each sheet of bacon S through the chute 20 in the manner described.

Although a sheet of bacon is specifically referred to throughout the specification, it is to be understood that the packaging device and the method of packaging may be used in packaging any type of flat substantially rectangular flexible or bendable article of substantially the same size as the wrapper or bag in which it is to be packaged.

In the drawings and specifications, there has been set forth a preferred embodiment of the invention and although specific terms are employed, they are used in a generic and descriptive sense only and not for purposes of limitation, the scope of the invention being defined in the claims.

I claim:

1. Apparatus for inserting relatively flat rectangular flexible articles, such as sheets of bacon, into open-ended bags of substantially the same shape and size as the articles comprising an open-top chute having an ingress section, an intermediate section and a bag holding section arranged in series and in alinement with each other, said ingress and intermediate sections each having a pair of upwardly diverging side walls, the side walls of the ingress section being connected to the side walls of the intermediate section and extending away from the intermediate section in diverging relation to each other, said bag holding section comprising a substantially trapezoidal bottom member and substantially triangularly-shaped side walls connected to opposite side edges of the bottom member and having their edges remote from the apex thereof connected to the edges of the upwardly diverging side walls of the intermediate section remote from the edges to which the walls of the ingress section are connected, and inwardly extending confining flanges on the upper edges of the side walls of the intermediate section and the ingress section, whereby a flexible planar article may be inserted between the side walls of the ingress section immediately beneath the inwardly extending confining flanges and slid along the ingress section and along the intermediate section and will be bowed as the opposite side edges thereof are moved toward each other to thus decrease the distance between opposite side edges of the article to permit the same to enter a bag positioned over the bag holding section.

2. A device to facilitate inserting flat substan-

tially rectangular flexible articles in open-ended bags of substantially the same shape and size as the articles comprising an open-topped substantially channel-shaped chute having an intermediate section provided with spaced parallel side walls, a rear section also having spaced side walls connected to the rear edges of the side walls of the intermediate section, the side walls of the rear section extending rearwardly in diverging relation to each other from their juncture with the walls of the intermediate section, the upper edges of the side walls of the rear and intermediate sections each having inwardly extending flanges thereon, a shovel-shaped front section having spaced side walls connected at their edges to the front edges of the side walls of the intermediate section, the upper edges of the side walls of the shovel-shaped section tapering forwardly from their juncture with the side walls of the intermediate section to facilitate positioning a bag over the shovel-shaped section, whereby an article of greater width than the distance between the upper edges of the walls of the intermediate section may be passed through the rear and intermediate sections successively with the opposite side edges beneath the flanges to cause the article to become bowed as the opposite edges of the article move toward each other to thus permit the article to be fed into the bag.

3. A device to facilitate inserting flat substantially rectangular flexible articles in open-ended bags of substantially the same configuration and dimensions as the articles comprising a chute having a substantially U-shaped intermediate section and a substantially U-shaped rear section, each of the intermediate and rear sections having upwardly diverging walls, the walls of the rear section being of substantially the same height as the walls of the intermediate section and having their front edges connected to the rear edges of the intermediate section, the walls of the rear section extending rearwardly from the intermediate section in diverging relation to each other, a flange extending inwardly from the upper edge of each of the walls of the intermediate and rear sections, said flanges extending the entire length of the upper edges of the corresponding walls, a U-shaped front section having upwardly and forwardly diverging side walls connected at their rear edges to the front edges of the side walls of the intermediate section, and the upper edges of the side walls of the front section each being cut at an angle and extending forwardly and downwardly from their juncture with the upper edges of the side walls of the intermediate section.

4. An open-top chute for packaging flexible planar articles comprising a U-shaped center section having relatively spaced substantially parallel side walls, a U-shaped rear section connected to the center section and having side walls diverging rearwardly from the center section, a U-shaped front section connected to the center section and having forwardly diverging side walls, said sections being in alinement, and article retaining means adjacent the upper edges of a portion of said chute.

5. A chute for packaging substantially rectangular sheets of flexible material in open-ended bags comprising an ingress section, an intermediate section and a bag holding section serially interconnected in alinement with each other, said ingress section comprising a bottom member wider at its outer edge than at its inner edge, upwardly diverging and inwardly con-

verging walls connected to the opposite side edges of said bottom, said intermediate section comprising a relatively narrow bottom member having upwardly diverging side walls connected thereto, said bag holding section comprising a 5 bottom member having a relatively narrow inner edge and a relatively wide outer edge and side walls connected to opposite sides of the bottom member of the bag holding section and diverging outwardly with respect to the intermediate section and being of a lesser height at their outer ends than at their inner ends, and an inwardly extending confining flange on the upper edge of each of the side walls of the ingress and intermediate sections whereby a bag may be slid over the bag holding section for opening the open end thereof and a sheet of flexible material may be slid between the walls of the ingress section

and thence between the walls of the intermediate section immediately beneath the confining flanges thereby bowing the sheet and decreasing the distance between opposite side edges of the sheet to permit the sheet to be slid into the bag.
